UNITED STATES PATENT OFFICE.

COLIN MACBETH, OF ASTON, BIRMINGHAM, ENGLAND, ASSIGNOR TO THE DUNLOP RUBBER COMPANY, LIMITED, OF LONDON, ENGLAND.

PUMP.

1,280,511.

Specification of Letters Patent. Patented Oct. 1, 1918.

Application filed March 15, 1916. Serial No. 84,356.

To all whom it may concern:

Be it known that I, COLIN MACBETH, a subject of the King of Great Britain, residing at Salford street, Aston, Birmingham, in the county of Warwick, England, have invented certain new and useful Improvements in or Relating to Pumps, of which the following is a specification.

This invention relates to pumps particularly those used for inflating pneumatic tires, the said pumps being of the kind in which the piston is operated by toggle members or links one of which forms a foot or hand operating lever for imparting movement to the piston against the influence of a spring.

The chief objects of this invention are to simplify and cheapen the construction by providing a more direct connection between the piston and the operating lever or pedal and to so construct the pump that the interior thereof is effectually protected from the ingress of dirt and grit from the boot of the operator in working the pump, and also when the pump is closed and out of use.

According to this invention, the pump comprises only three moving parts, viz.: the piston, an actuating lever or pedal, and a toggle link, which parts are so constructed and arranged in combination with a spring that the length of the pump is much less than that of pumps of the above kind hitherto employed, while the efficiency of the pump is increased. The said spring normally maintains the said parts in a position in which the piston is at the end of its suction stroke, and the lever or pedal raised, the delivery stroke of the piston being effected by depressing the lever. The toggle link is pivotally connected to a stationary portion of the pump and is also pivotally connected to the foot lever while the latter is pivotally connected directly to the piston at a point which is near the forward or delivery end of the cylinder when the piston is at the end of its delivery stroke, thereby avoiding the provision of additional parts such as a long piston rod and guide links or an elongated piston and cylinder as hitherto employed in certain forms of pumps of the above stated kind. The portion of the actuating lever which is con-

nected to the piston extends through an opening in the cylinder and lies between the pivotal points at the ends of the toggle link; the actuating lever is also so shaped as to constitute a protective cover which prevents the ingress of dirt and grit into the cylinder through the said opening therein when the pump is closed and inoperative or during the working of the pump.

In order that the said invention may be clearly understood and readily carried into effect, the same will now be described more fully with reference to the accompanying drawings, in which:—

Figures 1 and 2 are respectively a sectional elevation and a plan of one construction of the improved pump in the closed or inoperative position.

Fig. 3 is a similar view to Fig. 1 showing the pump open with the parts in position ready to effect the delivery stroke of the piston.

Fig. 4 is a sectional plan view of a portion of the pump taken approximately on the line 4—4 of Fig. 1.

Fig. 5 is a cross-sectional view taken on the line 5—5 of Fig. 1 looking in the direction of the arrows and drawn to a larger scale.

a represents the pump cylinder; *b* is the piston which is of trunk formation and is provided with a cup leather packing *b'* held in place by a plate *b²*. *c* is the actuating foot lever which is pivotally connected to the piston and *d* is the toggle member or link which is pivotally connected to the foot lever *c* and to a stationary part of the pump. *e* is the delivery head carrying a delivery valve *e'*, a flexible connecting tube *e²* and a pressure gage *e³* is secured to the forward end of the cylinder *a*; at the rear end of the cylinder is secured a cover of closing piece *f* which is formed with a carrying handle *f'*. The lower part of the delivery head *e* and the carrying handle *f'* are adapted to form feet which support the pump cylinder *a* in a horizontal position when in use. It will be seen that the cylinder *a* constitutes a frame or casing for the working parts so that a separate supporting frame is not necessary as in foot pumps hitherto employed. The cylinder *a* is provided with a semi-circular opening *a'* which as aforesaid

allows for the movement of the foot lever *c* and the toggle link *d*. The foot lever *c* is approximately semi-circular in cross section (see Fig. 5) so that when closed or depressed as shown in Fig. 1, it completely covers the semi-circular opening *a'* in the cylinder *a*; the inner side of the foot lever has a webbed lug or extension *c'*, the end of which is pivotally connected to a cross pin *b*³ secured in the piston *b*. The rear end of the foot lever is enlarged and provided with serrations *c*² to form good gripping surface for the operator's boot and an upstanding rim or ledge *c*³ is formed at the forward end of the foot lever for the purpose hereinafter mentioned. The toggle link *d* is in the form of a rectangular frame one end of which is pivotally connected to a cross pin *a*² fixed in the rear end of the cylinder while the opposite end is pivotally connected to a cross pin *c*⁴ secured to the inside of the foot lever *c* and the extension *c'* of the actuating lever is arranged to lie between the pivotal points at the ends of the toggle link *d*. A pair of tension springs *g* *g* connected to the piston *b* and to the cover piece *f* as shown, tend to maintain the piston at the end of its suction stroke with the foot lever *c* and toggle link or member *d* in the raised or open position shown in Fig. 3.

When the foot lever *c* is depressed by the operator's foot the toggle link *d* and the foot lever *c* are straightened thereby forcing the piston forward against the tension of the aforesaid springs to effect the delivery stroke. The alternate depression of the foot lever and the raising of the same by the action of the springs effect the reciprocation of the piston.

It will be seen from Fig. 3 that the curved shape of the foot lever and the upstanding ridge *c*³ formed on the lever shield the aforesaid opening from dirt and grit which might fall from the operator's boot during the working of the pump. A pivoted catch *h* is provided on an extension of the cover piece *f* to retain the foot lever *c* in the depressed position when the pump is not required for use. When the foot lever is retained in the depressed position it completely covers the opening in the cylinder.

The proportioning of the toggle link or member *d* and the foot lever *c* and the positioning of their pivot pins enable a relatively large movement of the piston *b* when commencing its delivery stroke, to be obtained by a small initial downward movement of the foot lever and toward the end of the delivery stroke a large downward movement of the foot lever produces a relatively small movement of the piston. The arrangement is also such that when the piston *d* reaches the end of its delivery stroke the foot lever and toggle link form (or approach the con-

dition of) straightened toggle levers, much more nearly than is the case with foot operated toggle pumps as heretofore made.

By disconnecting the foot lever *c* the piston can when necessary be removed from the cylinder through the aforesaid opening in the latter.

What I claim and desire to secure by Letters Patent of the United States is:—

1. A pump comprising in combination, a piston, a cylinder prolonged to form a rearward extension having an opening therein, an actuating lever extending through said opening and being directly pivoted to said piston and shaped to form a cover for said opening, a toggle link directly pivoted to said extension and to said actuating lever, and a spring connected to said extension and the piston.

2. A pump comprising in combination, a piston, a cylinder prolonged to form a rearward extension having an opening therein, an actuating lever extending through said opening and being directly pivoted to said piston and shaped to form a cover for said opening, and a single connection between said cylinder and actuating lever comprising a toggle link connected at its opposite ends to said cylinder and lever.

3. A pump comprising in combination a piston, a cylinder or casing, and a pivoted actuating lever having an upstanding rim at its forward end to prevent ingress of dirt or grit to the interior of said cylinder or casing.

4. A pump comprising in combination, a short piston an actuating lever pivoted to said piston, a toggle member or link pivoted to said actuating lever and to a stationary part of the pump, the actuating lever being of such formation that the part connected to the piston lies between the pivotal points at the ends of the toggle link.

5. A pump comprising in combination, a cylinder having a peripheral opening at its rear part, a piston adapted to reciprocate in the front or forward part of the cylinder, an actuating lever pivoted to said piston, a toggle link pivoted to said actuating lever and to the cylinder, the said actuating lever being of semi-circular or curved cross section to fit partly around the cylinder and cover said opening therein when the lever is in the lowered or depressed position.

6. A pump comprising in combination, a spring controlled piston, a cylinder having a peripheral opening at the rear part thereof, a delivery head at the front end of the cylinder and a carrying handle at the rear end, an actuating lever pivoted to the piston and a toggle member or link pivoted to the actuating lever and to the cylinder, the said actuating lever being shaped to close or cover said opening in the cylinder.

7. A pump comprising, a piston, a cylin-

130

der formed with a base or feet to support the cylinder horizontally, a carrying handle at the rear end of the cylinder, an actuating lever pivoted to the piston, a toggle member or link pivoted in said cylinder and to the actuating lever the said lever and toggle member being adapted to be moved through an opening in said cylinder and to be housed within the latter, the lever being shaped to cover or close the opening in the cylinder, and means to retain the lever in a depressed or inoperative position.

8. A pump comprising in combination a piston, a cylinder having a peripheral opening in its rear end, an actuating lever of curved or semi-circular cross section to cover said opening, a lug on said lever pivoted to the piston, a toggle member pivoted to said lever and to the cylinder, springs which maintain the piston at the end of its suction stroke with the lever and toggle link extending through the opening in the cylinder, and means to retain the actuating lever depressed

with the lug and the toggle link within the cylinder and the piston at the end of its 25 delivery stroke.

9. A pump comprising in combination a cylinder, a closing member at each end formed to support the pump, a carrying handle at the rear end of the pump, a piston in the forward end of the cylinder, springs to maintain the piston at the end of its suction stroke, an actuating lever having a lug pivoted to the piston, a toggle member or link through which said lug passes and which is connected to the lever and the cylinder, said cylinder being formed with an opening to allow for movement of the actuating lever and the toggle member, the actuating lever being so shaped as to prevent 40 ingress of dirt and dust through said opening into the cylinder and means to retain the actuating lever in a depressed or inoperative position.

COLIN MACBETH.
